DISPLAY DEVICE FOR MERCHANDISE

John Wallerowitz, Marion, Ill.

Application November 6, 1947, Serial No. 784,471

3 Claims. (Cl. 211—96)

1

The present invention relates to fixtures for display purposes, and more particularly has reference to display fixtures for attractively displaying various types of merchandise in stores and similar establishments.

The display device in its broadest aspect includes a vertically disposed support which may be removably attached to plate glass windows, walls or other suitable supporting surfaces. The support is so designed that its vertical position may be readily altered and, in addition, is provided with means whereby a bracket for supporting the device may be readily detachably secured thereto. In some instances, the support may carry a plurality of display racks for exhibiting different types of merchandise, and, in other instances, the support may carry but a single bracket. The bracket is so designed that the article supporting device may be disposed in a plurality of horizontal positions and maintained in the desired horizontal position.

An object of the present invention is to provide a support or holder for display brackets which may be readily secured to or detached from a supporting member such as walls, plate glass windows and the like.

And another object of my invention is to provide a holder for displaying merchandise which may removably support one or more display brackets.

Still a further object of my invention is to provide a display bracket for use with a supporting member of the character described which is provided with means for removably supporting the merchandise to be displayed.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 is a view in side elevation, partly in section, showing the display device employed with a plurality of brackets.

Figure 2 is a front view of the device shown in Figure 1.

Figure 3 is a sectional view taken along the line 3—3 of Fig. 2, looking in the direction of the arrows.

Figure 4 is a sectional view taken along the line 4—4 of Fig. 2, looking in the direction of the arrows.

2

Figure 5 is a sectional view taken along the line 5—5 of Fig. 2, looking in the direction of the arrows.

Figure 6 is a view in perspective of the removable bracket for supporting the merchandise to be displayed.

Figure 7 is a front view of a modified form of display fixture employing but a single bracket.

Figure 8 is a fragmental front view on an enlarged scale of the upper end of the support for the display bracket.

Figure 9 is a view in side elevation of the device shown in Fig. 8.

Figure 10 is a sectional view taken along the line 10—10 of Fig. 8, looking in the direction of the arrows.

Figure 11 is a sectional view taken along the line 11—11 of Fig. 8, looking in the direction of the arrows.

Figure 12 is a sectional view taken along the line 12—12 of Fig. 8, looking in the direction of the arrows.

Figure 13 is a fragmental front view showing a further modification of the display device used in connection with a wooden supporting surface.

Figure 14 is a sectional view taken along the line 14—14 of Fig. 13, looking in the direction of the arrows, and

Figure 15 is a sectional view taken along the line 15—15 of Fig. 14, looking in the direction of the arrows.

Referring to Figures 2 and 4, I have shown adjacent ends of a plate glass window front designated 10 which are joined by metal securing strips 11 provided with vertically spaced nut and bolt assemblies 12. My novel display device comprises an elongated channel member 13 which is provided with a slot 14 in the web of the channel. The supporting member 13 may

be secured to the metal securing strips 11 by removing the nut of the assembly 12 and by placing the bolts through the slot 14; the nuts are then drawn up on the bolts and the member 13 may be fastly maintained in any desired position with respect to the plate 10. A bracket for displaying the merchandise is adapted to be supported by the member 13, and this bracket is designated generally 15 and is best illustrated in Figure 6. The bracket 15 is preferably formed of sheet metal and includes a back plate

16 having a pair of opposed lugs 17 extending outwardly therefrom adjacent the lower end of the back plate. A horizontal shelf 18 extends forwardly from the upper edge of the back plate 16, and the front edge thereof is formed to provide a plurality of spaced upstruck elements

19 having horizontally disposed extensions 20 between each of the upstruck elements 19, and the purpose of these members will be herein-after more fully described.

A pair of side wings 21 extends forwardly from the back plate 16 and terminates adjacent the rearmost upstruck member 19 and it can be seen that the wings 21 are of considerably less height than the back plate 16. A front wall 22 joins the front end of the wings 21 and a bottom plate 23 closes the lower ends of the wings, thereby providing a box-like structure. An aperture 24 is formed in the shelf 18 and an aperture 25 is in vertical alinement with the aperture 24 in the plate 23. The alined apertures 24 and 25 are adapted to receive a vertical post 26 of a holder 27 which is employed to support a shelf or other structure upon which various articles of merchandise may be disposed. As shown in Figure 3, the holder 27 includes a horizontally extending arm 28 which is integrally joined to the post 26. By disposing the arm 28 between the desired upstruck elements 19 it will be readily appreciated that the holder may be held at various angles with respect to the bracket 15. By virtue of the upstanding members 19 and the horizontal elements 20, it will be readily appreciated that the holder 27 will be securely supported and will remain in the particular position desired until the vertical post 26 is removed from the alined apertures 24 and 25.

The member 15 is preferably, as above mentioned, a single blank of metal and is folded into the desired configuration, as shown in Figure 6.

To removably support the bracket 15 within the channel member 13, it will be seen in Figures 2 and 3 that each flange of the member 13 is provided at spaced intervals throughout the length of the channel with alined bayonet slots 29. The entering portion of the slot is of sufficient height to enable the lug 17 on the back plate 16 to enter and by moving the lugs downwardly into the vertical portion of the slot, it is obvious that the bracket 15 will be firmly held in proper position in the channel 13. This is a very simple attaching means and the bracket may be very quickly secured to or removed from the supporting channel 13.

With this particular form of the invention, a plurality of spaced brackets 15 are supported by the channel member 13 and each bracket may support, by virtue of the holder 27, a particular type of merchandise. For example, the uppermost bracket 15 may display shirts, pajamas, and similar articles of wearing apparel, whereas the bracket below may support shoes. To effect a more attractive display, the various holders can be held in different angular positions.

If it is desired to remove the display device, it is only necessary to remove each bracket 15 from its bayonet slot 29 and by unthreading the nuts on the assemblies 12, the channel member 13 may be easily removed from the supporting surface. The display holder in its entirety comprises but few, essential parts and the device may be very easily and cheaply fabricated.

In Figures 7 to 12, inclusive, there is shown another form of display device wherein a single bracket is employed. In this form, it can be seen that the support comprises an elongated metal strap 35 provided with an aperture 36 adjacent the upper end and a slot 37 near the lower end. The strap 35 may be attached to the metal securing strips 11 by the nut and bolt assemblies 12. A bracket 38 includes a hollow vertical spac-

ing member 39 provided with upper and lower horizontal shelves 40 and 41. The shelves 40 and 41 have an inner plane face 42 by which the bracket 38 is welded or otherwise secured to the strap 35. The remainder of the member 40 is circular in outline and is formed with a plurality of upstruck members 43 provided with horizontal extensions 44 between each of the upstruck members. Inwardly spaced from the outer edge of each horizontal extension 44 is an aperture 45 which is in vertical alinement with an aperture 46 formed in the shelf 41. The purpose of the apertures 45 and 46 is to receive the vertical post 26 of the holder 27 previously described in connection with the embodiment illustrated in Figure 1. The upstruck portions 43 and the extensions 44 function in the same manner as the elements 19 and extensions 20.

Manifestly, with this form there is provided a very simple construction for employing but a single display bracket, and by virtue of the aperture 36 and the slot 37, the strap 35 may be secured to the supporting surface in any desired location.

In Figures 13 to 15, inclusive, there is depicted a form of display bracket which may be employed with efficacy with wooden supporting surfaces. The bracket includes a back plate 50 having an aperture 51 near the upper edge thereof. A wood screw 52 extends through the aperture 51 and secures the plate 50 to a wooden securing strip 53 for the glass plates 10. The back plate 50 is bent at right angles adjacent its upper end to provide side plates 54. The side plates are tapered along the upper end, as shown at 55, and along the lower end, as indicated at 56. Disposed between the side plates 54 is a hollow box-like member 57 provided with a horizontal shelf 58 and a bottom closure 59. While the shelf is preferably welded to the upper edge of the box-like member 57 and to the back plate 50, it can, of course, be attached in other ways or be even integrally formed with the member 57. The outer edge of the shelf 58 is formed with upstruck lugs 60 having a horizontal extension 61 intermediate each lug. The plate 50 is notched above the lower edge thereof, as shown at 62, and each side is down-turned, as shown at 63, so that the back plate will readily conform to the securing strip 53. Hence, it can be seen that with this particular form, it is possible to provide a single display bracket for use with wooden supporting surfaces, and the bracket may be easily secured to or detached from the supporting surface by the proper manipulation of the screw 52.

As shown in Figure 14, the shelf 58 and the closure 59 are formed with apertures 64 and 65, respectively, and these apertures are in vertical alinement. The function of the apertures, of course, is to receive the vertical portion 26 of the holder 27 for supporting the holder in the bracket.

It will be appreciated from the foregoing description that there is provided a novel display device which, in the preferred form, will permit the vertically spaced brackets 15 to display various types of merchandise. By virtue of the upstruck members and the horizontal extensions provided between each of said members along the front edge of the bracket, it is possible to hold the display shelf which is carried by the holder in various angular positions. This arrangement is particularly efficacious, in that the articles displayed may be readily seen by

customers. The bracket and its component parts, namely the base member and the removable holder for the shelf or other display support are simple in structural detail and consequently can be inexpensively manufactured.

While I have shown the base member as being removably attached to the securing strip for adjacent edges of plate glass display windows, it is, of course, to be understood that this member may be secured to any vertical supporting surface such as a wall by means of suitable fastening devices.

I claim:

1. A device for displaying merchandise comprising a vertical member, a flat shelf extending horizontally from the upper edge of the vertical member, the free edge of the shelf being provided with a plurality of spaced apart flat horizontal extensions falling in the same plane as the shelf, upstruck elements on the shelf located on opposite sides of and rearwardly of the outer end of each extension, the shelf having an aperture therein, and a removable holder for the merchandise provided with a vertical portion adapted to be disposed on one of said extensions intermediate the upstruck elements whereby said holder is maintained in a desired position.

2. A device for displaying merchandise comprising a vertical member, a pair of spaced flat shelves extending horizontally from the vertical member, the free edge of the uppermost shelf being provided with a plurality of spaced apart flat horizontal extensions falling in the same plane as the shelf, upstruck elements on the shelf located on opposite sides of and rearwardly of the outer end of each extension, each of said shelves being provided with an aperture in vertical alinement, a holder for the merchandise having a vertical portion adapted to extend through said apertures, and a horizontal portion adapted to be disposed on one of said extensions intermediate the upstruck elements whereby said holder is maintained in a desired position.

3. A display device for merchandise comprising an elongated base member adapted to be removably secured to a supporting surface, a shelf having one edge affixed to the base member and extending horizontally therefrom, the free edge of the shelf being provided with a plurality of spaced apart horizontal extensions falling in the same plane as the shelf, upstruck elements on the shelf located on opposite sides of and rearwardly of the outer end of each extension, a second shelf beneath said first mentioned shelf and spaced therefrom, the second named shelf being secured at one edge to the base member and extending horizontally therefrom, said first mentioned shelf having an aperture rearwardly of each extension, said second named shelf having an aperture in alinement with each of said first named apertures, a holder for the merchandise provided with a vertical portion adapted to extend through the aligned apertures in said shelves and with a horizontal portion adapted to be disposed on one of said extensions intermediate the upstruck members whereby said holder is maintained in a desired position.

JOHN WALLEROWITZ.
